R. L. POULTON

DISPLAY STAND

Filed Sept. 12, 1927

R. L. Poulton

By Clarence O'Brien
Attorney

UNITED STATES PATENT OFFICE.

ROY LEWIS POULTON, OF COLUMBUS, OHIO.

DESIGN FOR A DISPLAY STAND.

Application filed September 12, 1927. Serial No. 23,390. Term of patent 14 years.

To all whom it may concern:

Be it known that I, Roy LEWIS POULTON, a citizen of the United States, residing at Columbus, in the county of Franklin, and State of Ohio, have invented a new, original, and ornamental Design for Display Stand, of which the following is a specification, reference being had to the accompanying drawing, forming part thereof.

I claim:

The ornamental design for a display stand as shown.

ROY LEWIS POULTON.
